UNITED STATES PATENT OFFICE.

HENRY J. RIVERS, OF ATTLEBORO, MASSACHUSETTS.

SAFETY CLASP FOR WATCH CHAINS.

Application filed May 6, 1927. Serial No. 189,385

This invention relates to safety clasps and in particular to one designed to be used in connection with a watch and chain and arranged to be attached releasably to the edge of 5 the vest.

A particular object of the invention is the provision of a watch chain vest safety clasp used to protect the watch from being broken as a result of its falling out of the pocket of 10 the vest when the same is hung up or when the clasp is secured to the vest, the watch is prevented from falling to the ground when the wearer stoops over as is commonly the case in the use of ordinary watch chains that are extended across the vest from pocket to pocket 15 to display the same.

A further particular object of my invention is to provide a clasp which will retard the action of a pickpocket and will give warning and also one which can be made to serve 20 as an ornament to hold lodge insignias so that they can be worn in connection with the watch chain instead of the coat lapel and also to hold initial signets which were formerly worn on 25 rings and lockets and other ornamental devices.

It is evident, also, that my invention may be used in a variety of different ways and one of the most important objects being the provision of a clip which may engage the edge of 30 the vest and which is positioned centrally of the watch chain and to which any particular insignia, signet, locket or other ornamental device may be attached, it of course being understood that the clip itself is in common use 35 for a variety of purposes and my invention is directed to the provision of a clip in connection with a signet or lodge insignia adapted to be worn in connection with a watch chain and 40 positioned at the edge of the vest at the center of the watch chain to give the ornamental effect desired.

To enable others skilled in the art to fully comprehend the underlying features that they 45 may embody the same in the various modifications in structure and relation contemplated, a drawing depicting a preferred form has been annexed as a part of this disclosure and in such drawings, similar reference characters denote corresponding parts throughout 50 all the views, of which,

Figure 1 is a view in perspective showing the watch chain as it would appear when worn having embodied therein my improved 55 safety clasp.

Figure 2 is a view in perspective of the

clasp showing the construction thereof and showing how the chain is secured thereto.

Figure 3 is a view in longitudinal section, 60 the particular safety clasp as shown in Figure 2, the ornamental member being used in connection with the clasp and its attachment thereto being illustrated.

Figure 4 is a view of a modified form of clasp having secured thereto the retaining 65 plate to which is also secured a locket showing how the same may be used in connection with a watch chain and safety clasp, and

Figure 5 is a plan view of the device shown in Figure 4, the locket being illustrated as it 70 would appear upon the vest of the wearer.

Referring to the drawings in detail, 5 indicates a watch chain of the well known variety to one end of which is secured the watch 6, positioned in the pocket of the vest 7 of the 75 wearer, the other end of the chain being arranged to hold a knife or other useful article which is usually positioned in the opposite pocket 8 of the vest. It is of course understood that the chain 5 extends across the chest 80 of the wearer and heretofore has not only hung loosely across the chest of the wearer but has not been secured to the vest in any manner so that theft is prevented or the watch is prevented from falling to the ground and 85 breaking.

With this improvement in mind, I have provided a clip member or safety clasp which comprises a lower jaw member 9 which is turned up at its forward end as at 10 to provide teeth, the forward end also intermediate the teeth being provided with an extended portion 11 in which is formed an eye 12 and to which the chain has connection to the jaw member 9, the opposite end of the jaw being provided with an extended portion 13 in which an eye also is formed, the chain at that end being indicated by the numeral 14 and being connected to the eye in the usual manner.

This bottom jaw 9 or member is provided with side ears 15 to which is secured depending ears 16 of an upper jaw member 17, the depending ears 16 and upstanding ears 15 being pivotally connected through the medium of a pivot pin 18 which passes therethrough and is headed at the opposite side to prevent separation of the jaw members of the clip or clasp. This pin 18 being arranged to carry a coil spring 19, the ends of which abut against both the top and bottom jaw members 17 and 9 respectively, so that the teeth formed on the front edge of the upper jaw member 17

and on the front edge of the lower jaw member 9 are normally in contact. This, of course, is readily understood and being necessary so that the clasp may grip the edge of the vest 5 to hold the device in position thereon.

In order to arrange an insignia in position on the clasp, I have shown a blank insignia plate 20 which is of fanciful shape and which may represent a lodge emblem, society emblem or any other device of an ornamental 10 nature, it being of course understood that this plate 20 is used for illustration purposes only and no ornamentation has been applied thereto except as shown in the perspective in Figure 15 to give an idea how the insignia might look if in position on the vest of the wearer.

The plate 20 at one end 11 is provided with an opening 12 in which the watch chain 5 is connected, the opposite end 13 of the plate 20 being also provided with an opening 14 through which the chain 5 is connected.

In Figure 4, I have shown a modified form 25 showing how the insignia plate might be otherwise secured to the clip, as in Figure 3, it is soldered as shown at 21 but may be secured in any other manner desired and in Figure 4, I have provided openings 22 in the top jaw member 17 of the clip through which may extend the tongue 23 formed in the locket 30 holding plate 24, these tongues being punched out of the locket plate and being forced through the openings 22 in the upper jaw member 17 so as to hold the plate in solid connection with the clip member indicated generally as at 25 and formed identically as above described with the exception of the chain holding extensions, which in this instance are provided on the ends of the plate 24, as illustrated.

40 The locket may be made of any desired construction and may include the case 26 and cover 27 in which is held the transparent member 28 and picture or ornamentation 29, it being of course understood that the bottom 45 of the locket is soldered or otherwise suitably secured to the locket plate 24 and thus does not take up the tension of the chain and is not subject to pull, the pulls of the chain being directly through the locket plate 24 which is 50 secured through the medium of the tongues 23, as before described to the clip members.

It is evident that the locket may be of any suitable size and in every instance the ornamental member is sufficient to cover or conceal the clip member so that it is not evident that the chain is being held in position on the vest and the insignia is properly displayed.

It is also evident that I have provided a 55 safety clasp for use in connection with vests and arranged to hold a chain, as a watch chain of the Waldemar type or any other type watch chain which will prevent the watch from being broken by reason of its falling 60 out of the pocket and which will prevent the

watch from becoming separated from the vest when the vest is thrown over the back of a chair or is hung in a closet or otherwise not in use.

It is further evident that it prevents the 70 stealing of the watch because any tug on the watch chain will be felt by the wearer and also the watch chain is rendered more ornamental by reason of the addition thereto of an insignia, lodge emblem or other ornamental feature.

75 It is evident therefore, that I have provided a clip which will add to the appearance of the wearer and one which may be made up at small cost, which may be used with a plurality of different emblems and one which 80 may be adapted for use with interchangeable emblems, lockets or other insignia.

While I have illustrated and described my invention with some degree of particularity, I realize that in practice various alterations 85 therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by United States Letters Patent is:—

90 1. A clasp for joining the sections of a watch chain comprising pivoted upper and lower gripping jaw members for engaging the clothing, a spring for normally urging the jaw members together and an insignia member secured to the upper one of said gripping members and arranged to conceal the same, and said insignia member being provided with openings for receiving the end link of the chain sections.

95 2. A clasp for joining the sections of a watch chain comprising pivoted upper and lower gripping members, adapted to grip the edge of a garment, the upper member having openings therein, a plate, lips on the plate arranged to enter the openings to secure the plate the upper member together and an ornamental member on said plate and the plate being provided with openings for receiving the end links of the chain sections.

100 3. A clasp for joining the sections of a watch chain comprising pivoted upper and lower gripping members, a spring for causing the members to normally grip the edge of a garment, the upper member having openings therein, a plate, lips punched out of the plate and arranged to enter the openings to secure the plate and the upper member together a locket member secured to said plate, and the plate being provided with openings 105 for receiving the end links of the chain sections.

110 In testimony whereof I affix my signature.
HENRY J. RIVERS. [L.S.]
